POWER UNIT FOR ACTUATING VALVES OR THE LIKE

John J. Dixon, Charlotte, N.C., assignor to Duff-Norton
Company, Charlotte, N.C.

Filed June 14, 1972, Ser. No. 262,781

Term of patent 14 years

Int. Cl. D15—99

U.S. Cl. D55—1 G

Fig. 3

Fig. 1

Fig. 2

Fig. 4

FIG. 1 is a front elevational view of a power unit for actuating valves or the like embodying my new design, the rear being the same as the front shown;

FIG. 2 is a side elevational view showing the actuator in an extended position, the opposite side being a mirror image of the side shown;

FIG. 3 is an enlarged top plan view; and

FIG. 4 is an enlarged bottom plan view.

I claim:

The ornamental design for a power unit for actuating valves or the like, as shown and described.
